(57) **CLAIM**

We claim the ornamental design for a motorcycle seat frame, as shown and described.

DESCRIPTION

FIG. 1 is a front perspective view of a motorcycle seat frame showing our new design;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is a rear perspective view thereof as installed on an exemplary motorcycle.

The broken line showing of the motorcycle illustrates environmental structure, while all other broken lines illustrate portions of the motorcycle seat frame. No subject matter shown in broken lines form part of the claimed design.
